AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

RETAINING DEVICE.

1,180,546.

Specification of Letters Patent. Patented Apr. 25, 1916.

Application filed May 23, 1914. Serial No. 840,482.

To all whom it may concern:

Be it known that I, AUGUST R. SCHOENKY, a citizen of the United States, residing at Somerville, in the county of Middlesex and State of Massachusetts, have invented certain new and useful Improvements in Retaining Devices, of which the following is a specification, reference being had therein to the accompanying drawing.

10 This invention relates to retaining devices, and is herein illustrated for convenience as applied for the purpose of retaining the bobbin within the shuttle of a lock stitch sewing machine, although obviously 15 the invention might be employed for analogous purposes.

More especially this invention relates to the class of retaining devices for sewing machine shuttles or bobbins involving an 20 arm or retainer which is pivoted adjacent to the shuttle box and is adapted to be swung between open and closed positions, so that it properly serves to hold the bobbin in the 25 face of the shuttle during the operation of the machine and may be opened when the machine is not operating, so as to permit inspection, replacement and repair.

An object of the present invention is to 30 generally improve and simplify retaining devices of the kind referred to and to provide an improved and simple means of normally effecting the locking of the retainer in closed position.

Another object is to provide a novel and 35 improved structure better than those heretofore known whereby, with the use of a single handle or operating device, the retainer may be both opened and shut, and when shut may be both locked and unlocked, 40 thus dispensing with the need of the operator employing both hands for opening or closing the retainer.

Other objects hereof will be elucidated 45 during the hereinafter following description of the present invention.

To the attainment of the above recited objects, the present invention consists in the novel features of combination, construction, arrangement and detail referred to and 50 illustrated in the accompanying description and drawings.

In the accompanying drawings forming a part hereof Figure 1 is a top plan view of an illustrative embodiment of the present

invention showing it applied to the retaining of a bobbin within a rotary shuttle, the retainer being in closed position. Fig. 2 is a view similar to Fig. 1 with the retainer in open position. Fig. 3 is a front elevation with the parts adjusted as in Fig. 1. Fig. 4 is a horizontal section on plane 4-4 of Fig. 3.

The present invention includes the novel combination with the retainer swingable between open and closed positions, of a brace 65 which is eccentrically pivoted to the retainer, or, what is the same thing, to a part rigid with the retainer, together with a suitable means that is operative when the retainer is closed and which serves to block 70 the pivoted brace against endwise movement whereby the retainer is locked closed, but is able to be opened by displacing the brace.

The invention also includes the combination with such retainer, brace and blocking 75 means, of a single handle which is adapted both to swing the brace into or out of the blocked position, and, when the brace is out of blocked position, to swing the retainer 80 open or shut; and specifically such handle is connected to the brace, and acts through the brace for swinging the retainer.

Referring more specifically to the drawings, a fixed portion 10 of the sewing machine frame supports the fixed shuttle box 11, in 85 which rotates the circular shuttle 12 which in turn carries the bobbin 13. The bobbin has a vertical projection 14 provided for the purpose of engaging with and being retained in position by the recessed portion 90 or head 15 of the swinging arm or retainer 16. Figs. 1 and 3 show the parts in their normal position, and in this position the shuttle 12 may be rotated or oscillated in any well-known manner, the bobbin 13 being held by the retainer 16 in either or both of two ways, namely, held against coming out of the shuttle and held through the projection 14 against rotation. It will be understood that the projection 14 and the recess in 15 have such relation that the under-thread or needle thread of the machine can be passed around the shuttle in forming 95 each stitch so as to interlock with the shuttle thread provided by the bobbin.

With the retainer 16 are comprised the following parts rigid therewith and substantially a part thereof, namely, the vertical

fulcrum shaft 17 formed with shoulders or steps to give it greater solidity of fitting, and, at the upper part of the fulcrum shaft, an enlargement 18 which may be considered 5 as a crank disk, as it affords the means for an offset or eccentric connection between the retainer and the brace, to be hereinafter described. The parts 16, 17 and 18, being rigid, swing together. Their further details 10 will be later described.

A novel and important element of the present invention is the brace 20 shown in the form of a strut or link, it being pivotally connected to the retainer at an eccentric 15 point and adapted to swing, as will be hereinafter described, into and out of its blocked position. Instead of connecting the brace 20 directly to the swinging arm portion of the retainer, it is shown pivoted at the top 20 side of the crank disk 18, which is rigid with the retainer. Such a pivotal connection is conveniently afforded by an upwardly projecting crank pin or stud 21 formed integral with the disk 18 and surrounded by 25 the hub portion at the left end of the brace 20. The free or swinging end 22 of the brace is the part thereof which is adapted to be blocked to preclude opening movement of the retainer when closed. For this purpose the end 22 may be in the form of a hub as at the left, so that the brace constitutes 30 a sort of link between the offset crank pin 21 and the blocking means.

Referring to Fig. 1, it is obvious that, 35 if the brace or link 20 can be held or blocked against movement when the retainer is closed, such action will effect the locking of the retainer. While the relative arrangement of the parts might be considerably 40 altered, the crank pin 21 in Fig. 1 is shown located to the rear of the fulcrum shaft 17, forming the axis of swinging of the retainer, and the brace 20 in this figure extends directly to the right. If now the right-hand end 22 of the brace be held so as to 45 prevent endwise movement of the brace, this will render the crank pin 21 absolutely immovable, so that the retainer becomes securely locked. The following constitutes 50 a convenient blocking means acting at the free end 22 of the brace to prevent endwise movement of the brace.

A blocking arm 24 is shown pivoted at its left at 25, and its right-hand end 26 is 55 pivotally connected to the right-hand end 22 of the brace. The parts are so arranged, designed and proportioned that the effective direction or axis of the brace and that of the blocking arm coincide in Fig. 1. In this 60 way the parts are in effect put upon a dead center, and the blocking arm effectually excludes endwise movement of the brace and, therefore, any movement of the crank pin and retainer. On the other hand, one 65 merely has to swing the free ends 22 and 26

and arm forwardly to throw the parts off dead center and permit or cause the opening of the retainer.

The connection between the swinging ends 70 22 and 26 and arm is shown in the form of a vertical fulcrum stud 28, and this conveniently forms a support for a handle 29 by which the swinging of the brace and arm may be effected.

By the described arrangement it will be 75 seen that the brace 20 not only forms a blocking device for locking the retainer closed, but, when the brace is moved from its blocked position, it is adapted to effect the opening of the retainer through the 80 connections between the brace and retainer. Therefore the handle 29 by a comparatively short movement in one direction, namely, forwardly, is able to first unblock the brace 20 and thereafter swing open the retainer, 85 leaving the parts in the position shown in Fig. 2, while the reverse movement of the handle 29, acting through the brace, first causes the retainer to swing closed and thereafter, upon reaching dead center, blocks 90 the brace and therefore locks the retainer shut. The described combination, therefore, attains the chief advantages hereinbefore recited.

Certain matters of preferred detail will 95 now be described. In order to assist the operator to bring the parts accurately to dead center without going beyond such position, there may be provided a yielding device or pin 32 indicating when the proper 100 adjustment is attained. This yielding pin or stop may be variously arranged, but is shown as coöperating with the underside of the blocking arm 24, which is properly constructed for the purpose. The pin 32 is vertically slidable through a screw cap 33, which retains it in position and also retains a helical spring 34 tending always to raise the pin. These parts for compactness and simplicity are located immediately within the crank pin 21, which stands up integrally from the disk 18 at the top of the fulcrum shaft 17. When the parts are in dead center, the brace 20, and consequently the crank pin 21, stand 110 directly beneath the blocking arm 24, and the blocking arm is provided with a sink or recess 35 directly above the stop pin 32 when the parts are in closed position. The blocking arm is also formed with an inclined approach or recess at 36 assisting the operator in forcing the blocking arm into position. As seen in Fig. 3, the top of the pin 32 is rounded and the recess 35 is conical, so that, while the parts are sufficiently held, 115 they may be disengaged by a quick forward pull upon the handle 29. Thus, the operator may unblock the brace and swing open the retainer by a forward movement of the handle, and by a rearward movement close 120 125 130

the retainer and bring the parts into dead center to block the brace, thereby locking the retainer.

It will be understood that when the parts 5 are in the position of Figs. 1 and 3, the retainer is locked in closed position. The exact position of the end or head 15 of the retainer arm is of some importance, and, in order to accurately position it when the 10 parts are locked, the following convenient adjusting means may be employed. The retainer arm at the point where it is rigidly connected to the fulcrum shaft 17 may be formed in two parts, namely, the lower and 15 left-hand part 39, which is directly keyed to the fulcrum shaft, and the part 40 from which the swinging arm actually extends. An adjusting screw 41 between the parts 39 and 40 permits slight relative adjustment 20 between them, so that the arm may be initially accurately positioned. A lock nut 42 serves to lock the adjusting screw 41 against accidental displacement.

In case it is desirable to limit the opening 25 or outward swinging of the retainer, for example, to the position shown in Fig. 2, such limitation may be effected by providing upon the retainer portion 39 a stop 45 which, when the retainer is swung open, 30 comes into contact with a fixed stop or lug 46 formed beneath the frame parts 10, as seen in Fig. 2.

The complete operation of the device will 35 be readily understood from the above description.

The original adjustment of the device is simple. Thus, the operator will adjust the members 20 and 24 to their dead center position shown in Figs. 1 and 3, and thereupon, with the lock nuts 19 and 42 loose, will adjust the screw 41 until the head 15 of the retainer stands in precisely correct position with respect to the shuttle. Thereupon the lock nut 42 will be tightened to 45 secure the screw 41, and lastly the nut 19 will be tightened to hold the retainer in rigid relation to the fulcrum shaft 17.

It will thus be seen that a retaining device has been described accomplishing the 50 objects and attaining the advantages hereinbefore referred to, and other advantages will be apparent to those skilled in the art. Since many matters of form, combination, arrangement, design and detail may be variously modified without departing from the principles hereof, no limitations to such features are intended excepting so far as specified in the appended claims.

What is claimed is:

1. Retaining means for sewing machine shuttles or the like comprising, in combination with a retainer swingable between closed and open positions, a brace movably mounted at an eccentric point upon, so as 55 to swing with the retainer, and to permit

shifting thereof relatively to the retainer, and a blocking member adapted to block the brace when the retainer is closed and thereby prevent opening of the closed retainer.

2. Retaining means for sewing machine 70 shuttles or the like comprising, in combination with a retainer swingable between closed and open positions, a brace eccentrically mounted upon the retainer in a manner to permit relative shifting thereof, and a 75 blocking member adapted to block the brace and thereby prevent opening of the closed retainer; said three elements so constructed and combined that a single shifting of the brace unblocks the brace and then opens the 80 retainer, while a reverse shifting closes the retainer and then blocks the brace.

3. Retaining means for sewing machine 85 shuttles or the like comprising, in combination with a retainer swingable between closed and open positions, a brace pivoted at an eccentric point upon, so as to swing with the retainer, and a blocking member, said elements so constructed and combined that when the retainer is closed the brace 90 may be swung into position to be blocked by said member against endwise movement, thereby locking the retainer closed.

4. Retaining means for sewing machine 95 shuttles or the like comprising in combination with a retainer swingable between closed and open positions, a brace pivoted at an eccentric point upon the retainer, and a blocking member, said elements so constructed and combined that when the retainer is 100 closed, the brace may be swung into position to be blocked by said member against endwise movement, thereby locking the retainer closed; and a control handle connected so that one operative movement thereof unblocks the brace and thereupon opens the 105 retainer.

5. Retaining means for sewing machine 110 shuttles or the like comprising in combination with a retainer swingable between closed and open positions, a brace pivoted at an eccentric point upon the retainer, and a blocking member, said elements so constructed and combined that when the retainer is closed, the brace may be swung into position 115 to be blocked by said member against endwise movement, thereby locking the retainer closed; and a control handle connected so that one operative movement thereof unblocks the brace and thereupon opens the retainer, the reverse movement acting through the brace to close the retainer followed by the blocking of the brace.

6. Retaining means for sewing machine 125 shuttles or the like comprising in combination with a retainer swingable between closed and open positions, a brace mounted at an eccentric point upon the retainer to permit a limited relative swinging movement thereof, and a brace-blocking member, 130

said elements combined so that when the retainer is closed the brace may be swung into and out of blocked position, and when the brace is out of blocked position the brace ⁵ may open and close the retainer.

7. Retaining means for sewing machine shuttles or the like comprising in combination with a retainer swingable between closed and open positions, a brace mounted ¹⁰ at an eccentric point upon the retainer to permit a limited relative swinging movement thereof, and a brace-blocking member, said elements combined so that when the retainer is closed the brace may be swung into and ¹⁵ out of blocked position, and when the brace is out of blocked position the brace may open and close the retainer, and a handle for shifting the brace in either direction whereby in a single handle movement the retainer ²⁰ may be unlocked then opened, or closed, then locked.

8. Retaining means for sewing machine shuttles or the like comprising, in combination with a retainer swingable between closed and open positions, a fulcrum and a crank, both comprised rigidly with the retainer, a brace pivotally mounted eccentrically on the crank, and a blocking member ²⁵ adapted to block the brace against endwise movement when the retainer is closed and the brace is swung into blocked position.

9. A retaining device for the described or analogous purposes, comprising in combination, a retainer fitted to swing between closed ³⁰ and open positions, a link pivotally connected to the retainer at an eccentric point, and

adapted to swing into and from blocked position, and a blocking arm pivotally mounted and having its free end pivotally engaged with the free end of said link, the parts so arranged and related that when the retainer is closed the link and the arm may be moved to dead center to block the link against endwise movement and thereby lock the retainer closed. ⁴⁰

10. A retaining device for the described or analogous purposes, comprising in combination, a pivoted retainer having a crank swinging therewith, an arm pivoted at a point eccentric to said retainer, and a link ⁴⁵ connecting said crank and arm, whereby when the arm and link are in alinement the retainer is locked, and displacement of link or arm causes swinging of the retainer. ⁵⁰

11. A retaining device for the described or analogous purposes, comprising in combination, a pivoted retainer having a crank swinging therewith, an arm pivoted at a point eccentric to said retainer, and a link connecting said crank and arm, whereby ⁵⁵ when the arm and link are in alinement the retainer is locked, and displacement of link or arm causes swinging of the retainer, a handle adapted to swing the link and arm into and out of alinement, and means for ⁶⁰ yieldingly retaining them in alinement. ⁶⁵

In testimony whereof I affix my signature in presence of two witnesses.

AUGUST R. SCHOENKY.
